Primary Examiner — Kevin K Rudzinski(74) Attorney, Agent, or Firm — Banner & Witcoff, Ltd.(57) CLAIM

The ornamental design for a shirt, as shown and described.

DESCRIPTION

FIG. 1 is a front view of a shirt showing my new design; FIG. 2 is a front-right side perspective view thereof; FIG. 3 is a right side view thereof; FIG. 4 is a rear-right side perspective view thereof; FIG. 5 is a rear view thereof; FIG. 6 is a rear-left side perspective view thereof; FIG. 7 is a left side view thereof; and, FIG. 8 is a front-left side perspective view thereof. The broken line immediately adjacent to the shaded area defines the bounds of the claimed design and forms no part thereof. The broken lines depicting the remainder of the shirt form no part of the claimed design.

1 Claim, 8 Drawing Sheets(56)
